[57] CLAIM

The ornamental design for a clothing display stand, substantially as shown and described.

DESCRIPTION

FIG. 1 is a front elevational view of a clothing display stand showing my new design;

FIG. 2 is a top plan view thereof;

FIG. 3 is a perspective view of a modified form of the clothing display stand shown in FIG. 1, the opposite sides not shown being identical thereto.
